UNITED STATES PATENT OFFICE

EDGAR E. KAHN, OF MOUNT VERNON, NEW YORK

DESIGN FOR A BOTTLE OR SIMILAR ARTICLE

Application filed January 27, 1932. Serial No. 42,641. Term of patent 3½ years.

To all whom it may concern:

Be it known that EDGAR E. KAHN, citizen of the United States, and resident of Mount Vernon, in the county of Westchester and State of New York, has invented a new, original, and ornamental Design for a Bottle or Similar Article, of which the following is a specification, reference being had to the accompanying drawing, forming part thereof, in which the figure is a perspective view of a bottle embodying my new design.

I claim:

The ornamental design for a bottle or similar article, substantially as shown.

Dated, January 26, 1932.

EDGAR E. KAHN.
